CURRENCY HAND TRUCK

Robert M. MacTarnahan, 11416 SW. Lynnridge,
Portland, Oreg. 97225

Filed Nov. 20, 1970, Ser. No. 26,100

Term of patent 14 years

Int. Cl. D12—02

U.S. Cl. D14—3

FIG. 1 is a front perspective view of a currency hand truck, showing my new design; and

FIG. 2 is a rear perspective view thereof.

The dotted lines are for illustrative purposes only.

I claim:

The ornamental design for a currency hand truck, substantially as shown and described.
